UNITED STATES PATENT OFFICE

160,500

SEWING MACHINE

Leon Jolson, Forest Hills, N. Y., assignor to Necchi
Sewing Machine Sales Corp., New York, N. Y.,
a corporation of New York

Application August 1, 1950, Serial No. 11,513

Term of patent 14 years

(Cl. D70—2)

To all whom it may concern:

Be it known that I, Leon Jolson, a citizen of no country, now a resident of Forest Hills, in the county of Queens, State of New York, have invented a new, original, and ornamental Design for a Sewing Machine, of which the following is a specification, reference being had to the accompanying drawing, forming a part thereof.

Figure 1 is front elevation showing my novel design for a sewing machine.

Figure 2 is an end view taken from the left side of Figure 1.

Figure 3 is an end view taken from the right side of Figure 1.

Figure 4 is a rear elevation of my novel design for a sewing machine.

Figure 5 is a top plan view of my novel design for a sewing machine.

I claim:

The ornamental design for a sewing machine, as shown.

LEON JOLSON.
